a corporation of New York

Application May 23, 1944, Serial No. 113,729

Term of patent 7 years

(Cl. D21—1)

To all whom it may concern:

Be it known that I, Jules Nisenson, a citizen of the United States of America and a resident of the Borough of Manhattan, city, county, and State of New York, have invented a new, original, and ornamental Design for Venetian Blind Cord Lock, of which the following is a specification, reference being had to the accompanying drawing, forming a part thereof.

Figure 1 is a front view in perspective of a Venetian blind cord lock, showing my new design.

Figure 2 is a rear view in perspective of the Venetian blind cord lock shown in Figure 1.

I claim:

The ornamental design for a Venetian blind cord lock, as shown.

JULES NISENSEN.
